UNITED STATES PATENT OFFICE.

EWALD F. PAWSAT, OF SHEBOYGAN, WISCONSIN.

DESIGN FOR A MUD-GUARD BRACE.

57,378.

Specification for Design.

Patented Mar. 15, 1921.

Application filed December 15, 1919. Serial No. 345,145. Term of patent 14 years.

To all whom it may concern:

Be it known that I, EWALD F. PAWSAT, a citizen of the United States, residing at Sheboygan, in the county of Sheboygan and State of Wisconsin, have invented a new, original, and ornamental Design for a Mud-Guard Brace, of which the following is a specification, reference being had to the accompanying drawing, forming part thereof.

The figure is a perspective view of a mud guard brace, consisting of an upper tapered yoke and downwardly extending supporting arms, showing my new design.

I claim:

The ornamental design for a mud guard brace, as shown.

EWALD F. PAWSAT.
